BATTERY TERMINAL CONNECTION

John G. Sutherland, Toronto, Ontario, Canada

Application July 17, 1943, Serial No. 495,393

4 Claims. (Cl. 173—259)

This invention relates to improvements in the means for connecting electric cables to battery terminals, and the principal object of the invention is to provide a connection which will ensure a proper electrical contact between the cable and the terminal post and which may be secured in position without the danger of injury to the post or battery cell through the application of too severe a pressure.

A further object is to provide a connector which may be easily and quickly attached or detached with the use of an ordinary spanner or wrench so that the necessity of the use of special gripping pliers, such as are often required with the present form of bolt-secured connectors.

A further object is to economize in the use of metal in the clamp.

The principal feature of the invention consists in producing a clamp stamped from sheet metal which will present effective gripping surfaces to the periphery of the terminal post, such gripping surfaces being in the form of threads which are engaged by an encircling nut, the thread and the threaded surfaces of the nut being tapered to ensure the easy placing of the nut and an increased tightening or constricting effect upon the thread surfaces engaging the post.

A further important feature consists in providing a nut to encircling the post and the threaded connecting member with small and large tapered threaded orifices to permit the reversing of the nut to accommodate variation in size in battery terminal posts.

In the accompanying drawing

Figure 1 is a perspective view showing my improved terminal post connector attached to a battery cable and ready for insertion over a terminal post.

Figure 2 is a longitudinal vertical sectional view through a post connector as illustrated in Figure 1 showing the fastening nut arranged on the upper end of the connector.

Figure 3 is a vertical transverse sectional view through the threaded post-engaging portion of the connector illustrated in Figure 1 and showing the fastening nut reversed from the position illustrated in Figure 2 with the larger threaded portion engaging the lower portion of the threaded connector.

Figure 4 is a transverse sectional view taken on the line 4—4 of Figure 1.

Figure 5 is a transverse sectional view taken on the line 5—5 of Figure 1.

Figure 6 is a plan view of the sheet metal blank as stamped out and prior to being folded into the form illustrated in Figures 1 and 2.

The ordinary form of battery terminal connector comprises a metallic ring of heavy cross section provided with a tapered orifice and having a radial slot extending between a pair of

lugs, the lugs being drawn together and clamped to the post by a transverse bolt.

With this type of connector, which is very common and almost exclusively used, it is necessary both in tightening and loosening the bolt to hold the head end of the bolt with a wrench or pliers while the nut is loosened at the other end with another tool, and specially formed pliers with right-angled projecting jaws are commonly used for loosening the nut. If the particular tools described are not available the loosening of the terminal connector bolt becomes a difficult operation and frequently the connector or the post, or both, are damaged as a result of the force applied to loosen the bolt which is peculiarly subject to corrosion in its environment on the battery post.

The present invention has been devised to overcome these difficulties and to provide a connector which may be securely attached to the cable in a very simple manner and then may be attached to the post or removed therefrom by the simple operation of turning a large nut which encircles the connector and post.

In the construction herein shown a length of sheet metal is stamped out substantially in the form illustrated in Figure 6 of the drawing. At one end of this metal stamping there is formed a transversely rectangular portion 1, the ends 2 of which are afterwards turned inwardly, as illustrated in Figures 1, 2 and 4, to overlap the end 3 of the battery cable.

A pair of narrow lugs 4 extend laterally from the metal strip adjacent to the rectangular portion 1 and these lugs are adapted to be turned inwardly over the central part of the metal strip in the opposite direction to the lugs 2 to form guides for the other terminal end 5 of the connector member when the strip has been formed up and folded.

Next adjacent to the portion of the blank from which the lugs 4 extend is formed a tapering threaded portion 6 which in being stamped is curved transversely to substantially the circumferential curve of the battery post which is tapered.

A narrow strip 7 connects the threaded portion 6 with a correspondingly threaded and divergent portion 8. Adjacent to the wide base end of the portion 8 the metal strip is widened into a circular washer formation 9 which has a central opening 10 of slightly larger diameter than the bottom diameter of the battery post, and the terminal end lug 5 extends beyond the washer portion 9.

The metal strip thus formed has the lugs 2 and 4 bent upwardly and downwardly respectively, and the strip 7 is bent at substantially right angles adjacent to the narrow ends of the threaded portions 6 and 8.

The washer portion 9 is bent in substantially

right angular relation to the threaded portion 8 and when the strip is thus bent the washer portion extends beneath the member 7 and is centrally arranged in relation to the two transversely curved threaded members 6 and 8.

In forming up the strip as thus described the end lug 5 is caused to extend under and parallel with the flat strip portion beneath the down-turned lugs 4. These lugs are then bent inwardly under the strip 5 to hold the structure in shape with the substantially frusto-conical threaded portion formed by the members 6 and 8 arranged either side of the top centre strip 7.

The fitting is then complete and ready for use and it is attached to cable 3 by simply inserting the end of the cable between the upturned lug portions 2 and the said lugs are then turned inwardly over the cable to grip it securely and the cable and lugs are securely soldered together.

A nut 11 is preferably formed with two spaced flanges, one slightly larger than the other and spaced apart by a groove 12. The smaller end 13 is threaded with a tapered thread corresponding in diameter with the threads at the upper frusto-conical ends of the member formed by the sections 6 and 8 of the metal strip, and the larger nut section 14 is threaded with a tapering thread of a larger diameter which fits the lower portion of the threaded frusto-conical member, as is illustrated particularly in Figure 3.

In the use of the battery terminal connector herein shown and described the threaded frusto-conical sheet metal portions of the formed-up member slips easily over the small diameter ends of the battery terminal post and drops down over its tapered surface.

The nut 11 may be placed over the threaded frusto-conical section of the connector, either before the said connector is placed on the post or after, and as both the nut and the frusto-conical section and the post are tapered the turning of the nut quickly tightens upon the threaded sheet metal member and squeezes the apexes of the thread on the inward side thereof into close engaging and embedding contact in the lead terminal post. Consequently a very excellent electrical contact is obtained and the large nut is easily engaged by a standard spanner or wrench and presents excellent gripping surfaces to the wrench, permitting the nut to be turned to ensure a firm grip between the threaded member and the lead post.

If the post is extra large the nut may be reversed to bring the larger threaded portion into engagement with the threaded frusto-conical gripping portion, or, if the upper threaded portion of the frusto-conical gripping portion should be marred the nut can be reversed so that the larger threaded portion thereof will extend further down on the gripping members and grip the post securely in another position.

It will be noted that the washer-shaped extension 9 extends under the bottom of the frusto-conical threaded portion of the connector and the lug 5 extends between the inturned lugs 4 so that it is held securely in position. The device is thus quite rigid and when being placed in position the terminal post first extends through the hole 10 of the washer and the entire structure is thus held securely in position on the post so that the outer threaded portion 8 of the gripper part of the

structure will not be distorted but both sections of the frusto-conical member will be held in proper alignment and the tightening of the nut thereon will not force them out of their proper position in engaging the threads of the nut.

From this description it will be appreciated that this device can be made up from comparatively light-gauge sheet metal in a stamping operation. It is first blanked out then formed up in the manner described and no machining whatever is required. The nut is of extremely simple construction and can be threaded with a single taper thread or dual threads as described.

The amount of metal used in a single connection will be greatly reduced from the standard connections at present in use which is an important consideration, and the device when applied to a battery post ensures perfect electrical contact even though the post may be mishapen through corrosion or otherwise. Further, the connector will easily slip on to posts which may be of different sizes.

What I claim as my invention is:

1. A battery terminal, comprising a length of sheet metal formed intermediate of its length with a substantially frusto-conical threaded portion to fit over a battery terminal post and having a socket extension from one end thereof to receive and hold a conductor cable and an extension from the opposite end having an opening therein to receive the terminal post, and a nut adapted to fit over the frusto-conical portion of said member and to compress same into close engaging electrical contact with the tapered post.

2. A battery terminal, comprising a strip of sheet metal having formed intermediate of its length and spaced apart by a narrow strip a pair of tapering and transversely curved threaded portions, said strip having a perforated washer-like extension to fit over a battery post, and an extension at the opposite end of said washer adapted to be secured to a cable.

3. A battery terminal, comprising a strip of sheet metal blanked out with a transversely arranged rectangular portion at one end providing lug extensions to be folded inwardly to embrace a cable, laterally extending lug portions arranged adjacent to said rectangular portion adapted to be turned inwardly, a pair of tapered and transversely curved and threaded portions spaced apart by a narrow strip, a washer extension from the end of the outermost of said pair of threaded members, and a lug extending from said washer extension adapted to be engaged by the inturned lug portions adjacent to the rectangular portion at the opposite end of the strip.

4. A battery terminal, comprising a pair of part-circular threaded sheet metal members connected by a narrow strip and adapted to fit over a tapering battery terminal post, a washer extension from the base of one of said threaded members adapted to fit over the battery post and having an extending lug, an extension from the base of the other of said tapered threaded members having lugs turned inwardly to embrace the side edges of the lug extension of said washer member, and an extension adjacent to the aforesaid lug members having inturned lug members to embrace a current cable.
